UNITED STATES PATENT OFFICE

2,280,005

WRENCH

William Petersen, De Witt, Nebr.

Application August 17, 1940, Serial No. 353,142

3 Claims. (Cl. 81—84)

This invention relates to wrenches and has relation more particularly to that type of wrench wherein is used a stub lever for coaction with an operator to effect a fine adjustment of the jaws of the wrench with respect to the work and it is an object of the invention to provide a wrench of this kind with means for holding the stub lever in effective position.

The invention consists in the details of construction and in the combination and arrangement of the several parts of my improved wrench whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view partly in side elevation and partly in section of a wrench constructed in accordance with an embodiment of my invention, a second position of certain of the parts being indicated by broken lines.

Figure 2 is a detailed sectional view taken substantially on the line 2—2 of Figure 1.

Figure 3 is a detailed sectional view taken substantially on the line 3—3 of Figure 1.

As disclosed in the accompanying drawing, 1 denotes an elongated handle member of channel formation of desired dimensions and configuration and which has its forward end portion formed to provide a fixed jaw 2, while the opposite end portion of the member 1 is formed to provide an interiorly threaded sleeve 3. The portion of the handle 1 immediately adjacent to the jaw 2 is transversely enlarged and pivotally mounted between the side walls 4 at said transversely enlarged portion of the handle 1, through the medium of the riveted pin 5 and the inwardly directed wing or flange 9 carried by the movable jaw 10.

The wing or flange 9 fits substantially snug between the side walls 4 of the handle member 1 and pivotally connected, as at 11, to the inner end portion of the jaw 10 is an elongated lever 12 which constitutes an operating handle. This lever or handle 12 is also of a channel formation and pivotally engaged by the pin 14 between the side walls 15 of the lever or handle 12 at a desired point inwardly of the pivotal connection 11 is an end portion of a stub lever or

fulcrum bar 16. This bar 16 is of a desired length and extends inwardly between the side walls 4 of the handle member 1 and has said inserted end portion transversely enlarged, as at 17, to provide a head for a purpose to be hereinafter more particularly referred to.

This head 17 has direct contact with the inner end of a shank 18 threaded through the sleeve 3. To facilitate this contact between the inserted end of the lever or bar 16 or more particularly of the head 17 with the inner end of the shank 18, said inner end of said shank 18 is provided with an outwardly extending reduced pin 19 which engages the inserted end or head 17 of the lever or bar 16. This inserted end or head 17 of the lever or bar 16 is provided with an outstanding lip 20 to facilitate a proper action of the lever or bar 9 upon movement of the shank 18 inwardly of the handle member 1.

20 The inserted end or head 17 of the lever or bar 16 is maintained in contact with the inner end of the shank 18 or more particularly the pin 19 thereof by the retractile member 21 herein disclosed as a coil spring of requisite tension. One extremity of this spring 21 is anchored, as at 22, to the movable jaw 10 and the opposite end portion thereof is anchored, as at 23, to the intermediate portion 24 of the handle member 1 at a desired distance rearwardly of the jaw 10.

25 The stub lever or fulcrum bar 16 at a desired point intermediate its ends is provided with a lug 25 for contact with the intermediate portion 26 of the lever or handle 12. This lug 25 is of such length whereby its contact with the intermediate portion 26 of the lever or handle member 12 will stop the relative movement of the lever or handle 12 and the handle member 1, one toward the other, before the pivot 14 passes over the line between the pivot 11 and the bearing point of the lever or bar 16 against the pin 19. By this means it is assured that the retractile member or spring 21 will be constantly effective to move the swinging jaw 10 away from the fixed jaw 2 when the lever or handle member 12 is in its innermost position with respect to the handle member 1.

30 The use of a stub lever or fulcrum bar is not new as such is embodied in the wrenches as comprised in my Patent No. 1,489,458 dated April 8, 1924, and my Patent No. 2,201,918, dated May 21, 1940. A disadvantage in the wrenches as disclosed in these former patents just mentioned resides in the liability of the stub lever or fulcrum bar falling out of the handle member 1 upon adjusting the lever or handle member 12

in an outermost position. To avoid this it is to be noted that the inner face of the handle member 1 immediately adjacent to the sleeve 3 is formed to provide a longitudinally disposed slot 21 of a length slightly longer than the movement of the shank 18 inwardly of the handle member 1. It is also to be noted, as illustrated in Figures 2 and 3, that this slot 21 is of a width less than that of the inserted end or head 17 of the lever or bar 16 and as particularly illustrated in Figure 3 it is to be noted that the inner end of the slot 21 is open.

The slot 21 may be formed by providing the inner marginal portions of the side walls 4 of the handle member 1 with inwardly disposed flanges 28.

It is believed to be obvious that under normal conditions the lever or bar 16 at no time will fall out of position within the handle member 1, although when desired the lever or bar 16 may be freed from the handle member 1 by manually forcing the lever or bar 16 inwardly whereupon the head 17 will pass out beyond the inner open end of the slot. It is not necessary to force the inserted end of the lever or bar 16 a distance to free the lip 20 as the major diameter of this lip 20 is less than the width of the slot 21.

From the foregoing description it is thought to be obvious that a wrench constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A wrench comprising a handle member of channel formation having a fixed jaw, a movable jaw pivotally attached to the handle member for coaction with the fixed jaw, an operating handle pivotally connected with the inner portion of the movable jaw and having movement toward or from the handle member, the end portion of the handle member remote from the fixed jaw having its inner face formed to provide an elongated slot open at its inner end, a shank carried by said slotted end portion of the handle member and having endwise movement inwardly or outwardly with respect to the handle member, a stub lever pivotally connected at one end to the operating handle, the opposite end portion of the stub lever having a head of a width greater than the width of the slot of the handle member, said end portion of the stub lever provided with the head normally working within the slot of the handle member and in contact with the inner end of the shank, and a retractile member interposed be-

tween the movable jaw and the handle member for constantly exerting pull upon the movable jaw and to maintain the stub lever in contact with the shank.

5 2. A wrench comprising a handle member of channel formation having a fixed jaw, a movable jaw pivotally attached to the handle member for coaction with the fixed jaw, an operating handle pivotally connected with the inner portion of the movable jaw and having movement toward or from the handle member, the end portion of the handle member remote from the fixed jaw having its inner face formed to provide an elongated slot open at its inner end, a shank carried by said slotted end portion of the handle member and having endwise movement inwardly or outwardly with respect to the handle member, a stub lever pivotally connected at one end to the operating handle, the opposite end portion of the stub lever having a head of a width greater than the width of the slot of the handle member, said end portion of the stub lever provided with the head normally working within the slot of the handle member and in contact with the inner end of the shank, and a retractile member interposed between the movable jaw and the handle member for constantly exerting pull upon the movable jaw and to maintain the stub lever in contact with the shank, said slot being of a length to terminate beyond the inner end of the shank when at the limit of its movement inwardly of the handle member.

3. A tool of the character described embodying a handle provided with a stationary jaw, a pivotally mounted jaw, a toggle including a pair of pivotally connected sections, one end of one of the sections of the toggle being pivotally connected with the pivot jaw, the free end of another of the sections of the toggle extending into and 30 freely movable lengthwise of said handle, an adjustable fulcrum with which said free end of said toggle section engages, the last said end of the toggle section being enlarged, the portion of the handle in which said enlarged end moves 35 being of channel formation, portions of the handle being shaped to form overhanging portions of substantial length and shaped to form a slot of substantial length between the adjacent edges of said overhanging portions, said 40 slot being open at one end, the enlarged portion of the toggle section being movable under said overhanging portions of the handle, the toggle section operating in said slot whereby the free end of the last said toggle section will at all 45 times, regardless of the position of said adjustable fulcrum, be maintained against separation from the handle and a hand engaging portion connected with one of the sections of said toggle for actuating the toggle to swing said 50 pivotally mounted jaw about its pivot and said toggle element upon its fulcrum.

WILLIAM PETERSEN.
